UNITED STATES PATENT OFFICE.

JULES HUSSER, OF PITTSBURG, PENNSYLVANIA.

LIFE-SAVING DEVICE FOR BOATS.

No. 855,890.

Specification of Letters Patent.

Patented June 4, 1907.

Application filed March 20, 1907. Serial No. 363,370.

To all whom it may concern:

Be it known that I, JULES HUSSER, a citizen of the United States of America, residing at Pittsburg, in the county of Allegheny and State of Pennsylvania, have invented certain new and useful Improvements in a Life-Saving Device for Boats, of which the following is a specification, reference being had therein to the accompanying drawings.

10 This invention relates to a life saving device for boats, and the invention has for its object to provide a novel device that can be readily attached to boats having decks, the device being particularly designed for submarine boats.

15 My invention aims to provide an auxiliary vessel for carrying the crew and passengers of a boat to the surface of the water, should the boat sink or become disabled while traveling under the water. I employ novel means for holding the auxiliary vessel upon a boat and releasing the same after the crew and passengers have entered the vessel.

20 The detail construction entering into my invention will be hereinafter more fully described and then specifically pointed out in the appended claims.

25 Referring to the drawing forming part of this specification, like numerals of reference 30 designate corresponding parts throughout the several views, in which:

30 Figure 1 is an elevation of a boat equipped with my improved life saving device, Fig. 2 is an enlarged cross sectional view of my improved device taken on the line $x-x$ of Fig. 1, Fig. 3 is a horizontal sectional view of the device.

35 In the accompanying drawing I have illustrated an ordinary boat 1, the deck 2 of which is provided with an oval opening 3, while the under deck or hull of the boat is provided with a threaded socket 4. Adapted to fit in the oval opening 3 of the deck 2 is an auxiliary vessel consisting of a convex cap 40 45 5, said cap being provided with a depending flange 6 to which are secured two plates 7, these plates forming a concave bottom for the auxiliary vessel. The cap 5 overlies the edges of the opening 3 and is provided with a gasket 8 to cushion the auxiliary vessel upon the deck 2.

50 Surrounding the depending flange 6 of the cap 5 is a pneumatic tube 9, said tube serving to float the auxiliary vessel when released.

The plates 7 are flanged, as at 10, and form a sleeve 11 centrally of the vessel. Passing through the sleeve 11 is a pipe 12, said pipe within the vessel being provided with radially disposed arms 14, whereby said pipe can be rotated. The upper end of the pipe is 60 provided with a head 15 having a cavity 16 formed therein communicating with radially disposed openings 17. The head 15 is threaded in an opening 18 formed in the cap 5. Normally the openings 17 are closed. 65

The lower end of the pipe is threaded, as at 19, to engage in the socket 4, and adjacent to the threaded end of said pipe are two openings 20.

70 The plates 7 are provided with diametrically opposed eyelets 21, to receive the ends of turn buckles 22, the object of which will be presently described.

75 Normally one of the plates 7 is removed, and assuming that the auxiliary vessel is used in connection with a submarine boat that has been disabled while submerged, the crew enters the auxiliary vessel, and stand upon the fastened plate 7. The other plate is then lifted into position and drawn into 80 engagement with the fixed plate 7 by the turn buckles 22. The plate 7 can then be further secured by bolts and nuts 23 arranged at intervals around the vessel. Immediately upon the vessel being closed, the pipe 12 is 85 rotated until the openings 17 rise above the cap 5, and the pipe becomes detached from the socket 4. Water then passes through the openings 17, cavity 16, pipe 12 and openings 20, filling the submarine boat and immediately upon the auxiliary vessel being elevated by the water within the submarine boat, the auxiliary vessel floats to the top of the water. The pipe 12 can then be rotated 90 to remove the head 15 from the threaded opening 18 of the cap and the crew can be removed one at a time through said opening. 95

100 It will of course be understood that the head 15 is withdrawn into the vessel after the same has reached the surface of the water, thus admitting air until such a time as the crew can be rescued from the auxiliary vessel. Numerous other appliances can be used within the vessel to prevent suffocation and suitable bunkers can be provided for the storage of food and other necessities.

105 My improved life saving device is constructed of strong and durable metal, and

can be made of various sizes according to the type of boat in connection with which the same is used.

What I claim and desire to secure by Letters Patent, is:—

1. A life saving device comprising an auxiliary vessel adapted to be mounted in the deck of a boat, said vessel consisting of a cap, plates detachably secured to said cap, a pneumatic tube surrounding said cap, a vertically disposed pipe mounted for rotation in said vessel and adapted to detachably hold said vessel in engagement with a boat, an enlarged head carried by said pipe and having openings formed therein communicating with said pipe, said openings being normally closed by said cap, and means within said vessel for rotating said pipe and simultaneously releasing said vessel and flooding the boat.
2. The combination with a boat, of an auxiliary vessel

vessel detachably secured thereto, said vessel consisting of a cap, bottom plates carried thereby, a pneumatic tube surrounding said cap, a pipe mounted in said vessel and detachably connected to said boat, means to rotate said pipe and simultaneously release said vessel and flood said boat.

3. The combination with a boat, of an auxiliary vessel detachably secured thereto, said vessel consisting of a cap, bottom plates carried thereby, a pipe mounted in said vessel and detachably connected to said boat, means to rotate said pipe and simultaneously release said vessel and flood said boat.

In testimony whereof I affix my signature in the presence of two witnesses.

JULES HUSSER.
